UNITED STATES PATENT OFFICE

161,008

ROTARY MOWER HOUSING

Joel G. Doyle, Kansas City, Mo.

Application March 24, 1949, Serial No. 1,600

Term of patent 14 years

(Cl. D40—1)

To all whom it may concern:

Be it known that I, Joel G. Doyle, a citizen of the United States, residing at Kansas City, in the county of Jackson and State of Missouri, have invented a new, original, and ornamental Design for a Rotary Mower Housing, of which the following is a specification, reference being had to the accompanying drawing, forming a part thereof, in which

Fig. 1 is a top plan view of a rotary mower housing embodying my new design,

Fig. 2 is a side elevational view thereof, and
Fig. 3 is a bottom plan view thereof.

I claim:

The ornamental design for a rotary mower housing, as shown.

JOEL G. DOYLE.
